FIG. 7.

FIG. 6.

FIG. 5.

FIG. 1 is a front perspective view of a stage section showing my new design;

FIG. 2 is an end view of one end of the stage section shown in FIG. 1, the opposite end being rectangular and planar;

FIG. 3 is a side elevation view, as viewed from the left side of FIG. 1, the side opposite being a mirror image thereof;

FIG. 4 is a fragmentary sectional view, as viewed along line 4-4 of FIG. 1;

FIG. 5 is a top plan view of a stage section shown in FIG. 1;

FIG. 6 is a top plan view similar to FIG. 5 showing a slightly modified form of stage section; and

FIG. 7 is a top plan view of a further stage section showing a further slightly modified form thereof.

The undisclosed sides of the two additional embodiments are substantially identical to those disclosed in the first embodiment.

I claim:

The ornamental design for a stage section, substantially as shown and described.
